UNITED STATES PATENT OFFICE.

NICOLAS GYMINAITIS, OF SANTA BARBARA, CALIFORNIA.

WATER COOLING AND FILTERING APPARATUS.

Application filed February 24, 1926. Serial No. 90,277.

My invention relates to apparatus for cooling liquids and more particularly, although not necessarily to apparatus for cooling water immediately before filtering 5 the same.

It is a purpose of my invention to provide an apparatus of the above described character which includes a fan adapted to be operated by the passage of water through 10 the apparatus to create a circulation of air within the apparatus and in such manner as to secure a rapid cooling of the water.

It is also a purpose of my invention to provide a cooling apparatus in which a filtering member may be associated with the discharge opening of the apparatus for effecting a filtering of the water subsequent to the cooling operation.

Although I will describe only one form 20 of water cooling apparatus embodying my invention and point out the novel features thereof in claims, it is to be understood that various changes and modifications may be made herein without departing from the 25 spirit and scope of such claims.

In the accompanying drawings,

Figure 1 is a view showing in vertical section one form of cooling and filtering apparatus embodying my invention.

Fig. 2 is a fragmentary transverse sectional view taken on the line 2-2 of Fig. 1.

Fig. 3 is a transverse sectional view taken on the line 3-3 of Fig. 1.

Fig. 4 is a transverse sectional view taken on the line 4-4 of Fig. 1.

Fig. 5 is an underneath view taken in the direction of the arrow 5 of Fig. 1.

Referring specifically to the drawings in which similar reference characters refer to similar parts, my invention comprises in the present instance a casing or container designated generally at K and including a lower section k, an upper section k', and an intermediate section k², the latter section being threadedly associated with the top and bottom sections as clearly shown in Fig. 1. The top section k' is closed by a cover 15 threadedly associated therewith and provided axially thereof with an inlet snout 17 exteriorly threaded to receive a nut 18 which when fed upwardly effects a construction of a wedge-shaped split collar 19 to effectively clamp the apparatus to a spigot or water pipe 20. At a point within the cover 15 an inlet port 21 is formed and this port has communication with a pipe 22 mounted

for rotational movement by means of ball bearings 23 arranged between members 24 and 25 grooved to form raceways. The member 24 is cast on the upper end of the pipe 22 and is formed with a conical socket adapted to receive a correspondingly shaped projection provided on the under side of the cover 15 constituting a continuation of the port 21. The pipe 22 extends through the upper side 27 of a stator designated generally at S with its lower end formed with a conical thrust bearing 28 mounted in the lower plate 29 of the stator as clearly shown. Ball bearings 30 are associated with the bearing 28 so that in conjunction with the bearings 23 the pipe 22 can rotate with the least possible friction. This pipe 22 in reality constitutes a shaft of a water turbine including the stator S and a rotor designated generally at R. This rotor R is fixed to the shaft 22 and includes a casing 31 in which is arranged partitions 32 to define a plurality of spirally disposed passageways 33, as clearly shown in Fig. 3. These passageways 33 have their outer ends open for communication with vanes 34 formed at intervals upon the inner periphery of the stator S and arranged substantially tangential to the rotor as clearly shown in Fig. 3.

The lower wall 29 is formed with suitable openings at points between the vanes 34 in which are arranged the upper ends of coils of pipe designated at P, such coils being arranged radially with respect to the vertical axis of the casing, and the pipe of each coil being formed of any suitable material by means of which evaporation of the liquid traversing the pipe is effected. I preferably form the coils of pipe of clay, although it is to be understood that any suitable form of material can be used. These coils are sustained within the stator by means of threaded collars 35, while their opposite ends are supported within a bracket designated at B sustained on a depending rod 36 secured to the stator S. The lower ends of the coils are disposed in an annular series and directly above a discharge spout 37 threadedly mounted in the lower section k and containing a filtering block 38 formed of tripoli or other suitable material.

As clearly shown in Figs. 1 and 2, the upper section k' of the casing K is provided with an annular series of openings 39, and through these openings air is adapted to be admitted to the casing under the action of a

rotating fan N keyed to the pipe 22 in the manner shown in Fig. 1.

The spigot or water pipe 20 is illustrated as having a screen 41 at its lower end within 5 the inlet spout 17. This screen may have filtering material therein if desired. The spigot 20 can also be attached to a water faucet 42 if desired.

The discharge spout 37 has an upward extension 43 within the casing K and the discharge ends of the porous pipes P discharge directly into this upward extension. A series of apertures 44 are positioned around the base or lower end of the casing K. A cone-shaped plate 45 is secured to the casing outwardly from the apertures 44. This plate does not meet the outward extension 43 of the spout, there being an annular space 46 therebetween, for the circulation of air.

20 In practice the cooling and filtering apparatus is adapted to be associated with a spigot, faucet or any pipe from which water is discharged under pressure. The water leaving the spigot 20 passes downwardly 25 through the inlet spout 17, port 21, pipe 22 into the rotor R of the turbine. By virtue of the partitions 32 the water is caused to traverse the several passages 33 and because of the arrangement of the vanes 34 it will be 30 clear that the water effects rotation of the rotor R, thereby actuating the fan N. The water is expelled from the stator S through the several coils of pipe P and primarily discharged into the lower end of the latter into 35 the upward extension 43 of the spout 37 above the filter block 38. Thus there may be a head of water on the filter block to the height of the extension 43 of the spout.

40 Under the action of the rotating fan air is drawn into the casing through the openings 39 and forced downwardly, circulating about the coils P to effect rapid evaporation and consequent cooling of the water traversing the pipes. The air passes out of the casing through the annular space 46 and the apertures 44 on the base. The pressure of the water is such as to percolate the filter block 38 and in passing therethrough a filtering of the water is effected so that when it is 50 finally discharged from the spout 37 it is both cooled and filtered.

Having described my invention what I claim is:

55 1. A liquid cooling apparatus adapted to be associated with filtering means, comprising a casing, a water turbine within the casing, means for conducting water to said turbine, coils of porous pipe for receiving water from said turbine, a fan operated by 60 said turbine for creating a movement of air within the casing and around said coils, a discharge spout removably secured in said casing.

65 2. A liquid cooling apparatus adapted to be associated with filtering means, comprising

ing a casing, a water operated turbine mounted within the casing and including a hollow shaft, a rotor fixed to the shaft and formed with spirally arranged passageways, a stator, vanes carried by the stator and disposed substantially tangential of the periphery of the rotor, porous water receiving pipes communicating with the stator and a discharge spout adapted to receive a filtering block arranged within the discharge 75 spout and disposed adjacent the discharge ends of said pipes; and a fan fixed to the rotor shaft for the purpose described.

3. A liquid cooling apparatus adapted to be associated with filtering means, comprising a casing having air inlet openings formed therein, a fan mounted for rotational movement within the casing and adjacent said openings, a water turbine for actuating said fan, means for supplying water under pressure to said turbine, pipes for receiving the water from said turbine, said pipes being formed of a porous material and arranged to be exposed to the draft of air created by said fan, and a discharge spout for said casing provided with means for retaining a filtering block within said spout.

4. A liquid cooling apparatus adapted to be associated with filtering means, comprising a casing having openings formed adjacent the upper end thereof, a turbine sustained within the casing and including a stator, a rotor, a tubular rotor shaft journaled in the stator, a fan connected thereto, an inlet port through which water is supplied to the rotor shaft, clay pipes in communication with the stator for receiving the water from the turbine and a discharge spout adapted to retain a filtering block arranged adjacent the discharge ends of said pipes for the purpose described.

5. A liquid cooling apparatus comprising in combination a water turbine, a casing surrounding said turbine, a fan in the casing operated by the water turbine, a series of porous pipes leading the water discharge from the turbine, means to feed water to the upper part of the turbine, openings in the casing for the in and out flow of air and a discharge spout for the casing.

6. A liquid cooling apparatus comprising in combination a casing, means to attach said casing to a water spigot at the upper end of the casing, forming an inlet, a series of air apertures adjacent the upper part of the casing, a water spout adjacent the lower end of the casing, a series of air outlets adjacent the spout, a water turbine having a stator and a rotor, means connecting the rotor to the water inlet of the casing, a series of porous pipes connected to the discharge of the stator, the said pipes emptying into the said spout and a fan operated by the rotor.

7. A water cooler comprising in combina-

tion a substantially cylindrical casing having an inlet spout at its upper end, a discharge spout at its lower end, the discharge spout having an upward extension into the 5 casing, there being a series of air apertures at the upper portion of the casing and at the lower portion adjacent the spout, a water turbine mounted in the casing having a stator supported by the casing, a rotor 10 having an upwardly extending pipe, the said

pipe being connected to the inlet spout, a series of porous pipes extending downwardly from the stator the pipes having reverse bent coils and outlet ends fitting in the upward extension of the discharge spout and a fan 15 attached to the pipe extending upwardly from the rotor.

In testimony whereof I have signed my name to this specification.

NICOLAS GYMNAITIS.
